poration, South Bend, Ind.

Filed May 11, 1962, Ser. No. 193,924

6 Claims. (Cl. 51—13)

This invention relates to machines and methods for cleaning up castings or the like; and more particularly to an improved machine system embodying alternative bypass and cycling arrangements, whereby a single machine system may be efficiently employed to perform sequentially rough cleaning and finish cleanup processes on castings or the like such as contain widely different debris and sand loads.

Previously, centrifugal blast type machines have not been found feasible for use in single process treatments of certain workpieces such as castings direct from the molds, because such machines do not operate efficiently under greatly varying sand and debris loads. The present invention, however, provides in a single blast machine system, means for selectively passing refuse and spent shot through alternative cycling and temporary storage systems; whereby the blast machine component of the system operates at all times at the peak of its efficiency. More specifically, for example, the machine is more efficiently operable to sequentially knock out the cores and otherwise roughclean the castings, and then to finish-clean the castings without intermediate transfers or other handling of the castings. Hence, the time loss and labor and capital expenses heretofore necessarily inherent to use of prior type machines and systems for such purposes are eliminated. Other objects and advantages of the invention will be apparent from the specification hereinafter, having reference to the accompanying drawings wherein:

FIG. 1 is a somewhat schematic elevational view with portions broken away to show interior details, of one form of machine system of the invention; and

FIG. 2 is a view similar to FIG. 1 but of a modified system arrangement of the invention.

As shown in FIG. 1 of the drawing, a machine system of the invention may be constructed generally to comprise a workpiece support and carrying device such as a blast unit 10 including a cradle type conveyor 12 which supports and tumbles the load of castings which are to be processed, as indicated at 15. A shot throwing machine as indicated at 16 is disposed above the load of castings and operates to sling shot or other blast media against the workpieces at certain stages of the process as will be more fully explained hereinafter. The hopper and feed chute for supplying blast media to the unit 16 is indicated at 18, and the conveyor for carrying away spent media and debris is indicated at 20.

With a view to simplification of this specification the workpiece support and centrifugal blast machine components referred to will not be illustrated and described in further detail; the construction and operation of typical examples thereof being fully disclosed and explained respectively in U.S. Patents 2,104,055 and 2,819,562. However, it is to be understood that in lieu of the specific form of workpiece supporting and tumbling and shot throwing devices illustrated herein and disclosed in the referenced patents, any other suitable form of blast equipment may be employed; such as for example swing table machines as disclosed in U.S. Patent No. 3,041,786.

In any case in accord with the present invention the blast machine 10 is coupled into a blast media and debris circulating and separation system which may include an elevator 22 shown as discharging the debris and abrasive

2

mixture from the machine 10 through a cross conveyor 24 to a separator 28. The construction and operation of a separator of the preferred form is illustrated and described in full detail for example in my copending U.S. patent application Ser. No. 831,525, filed August 4, 1959. The separator includes a sand or "refuse" discharge spout 29 delivering into any suitable take-away device as indicated at 30; and a reconditioned blast media discharge chute 32 delivering into the foot of a second elevator 34. Elevator 34 delivers to a cross conveyor 36 which has a primary delivery into another separator 37 which delivers reconditioned shot to the hopper 18. Feeding of shot from the hopper 18 to the blast machine 16 is controlled by a valve 40. The separator 37 is of the type disclosed in detail in U.S. Patent 3,005,547, dated October 24, 1961. The conveyor 36 has a secondary delivery through a control valve 42 to a storage or surge tank 44 for purposes which will now be explained; discharge from the bin 44 into the elevator 22 being controlled by a valve 46.

In operating the system of FIG. 1, when the castings to be processed have been stripped from their molds they are loaded by any suitable means into the blast cabinet 10 of the machine; the valves 42, 46 being open. The door of the cabinet is then closed and if the castings contain appreciable quantities of loose sand or other core or mold debris the castings may first be tumbled and/or turned for a predetermined time to cause the more easily displaced sand and core materials to fall out of the castings. During this phase of the process the blast unit 16 may or may not remain idle, as preferred. In any case, the sand and debris falling from the workpieces into the conveyor 20 is passed first to the separator 28 from which much of the debris and non-reusable blast media are discarded at 30. However, any sand and debris not removed during this first pass through the separator 28 is automatically sent on through the elevator 34 and conveyor 36 and open valves 42 into the surge bin 44. From the surge bin the mixture then flows at reduced rate back again to elevator 22 for repass through the separator 28 whereby further debris is removed until the system is substantially cleared by discharge of the waste material by the separator.

In the meantime the blast unit 16 is activated with valve 40 open. Hence, as the workpieces continue to be tumbled they are pelted with blast media operating to clean up the workpieces by dislodging further sand, scale, etc. therefrom, as is well known in the art. When the bulk of the initially dislodged surge of debris has been discarded and/or absorbed by the surge bin, the valve 42 is closed and the mixture of spent blast media and additionally dislodged debris is now carried by the conveyor and elevator system first to the separator 28 and then to the separator 37 for normal separation and cleaning operation, and so that the reconditioned blast media may be again delivered to the hopper 18 and from thence recycled through the blast machine 16.

Throughout this phase of the operation, the valve 46 is controlled to permit only a reduced flow rate therethrough, and as the amount of debris dislodged from the work decreases, the separators 28, 37 "catch up" with the debris backlog and the percentage of debris in the mixture being handled by the separators falls off rather sharply. Thus, the previously stored excess debris initially residing in the surge bin 44 is slowly drawn off through the valve 46, and is fed into the cleaning system, whereby it is eventually all transported through the separators 28, 37 and all waste materials thereof eliminated.

By virtue of this machine arrangement the large initial surge loads of sand and debris which occur when the cores are being dislodged from the castings are temporarily side-tracked to the surge bin, whereby flooding of the separa-

tors is avoided. Also, in accord with the present invention the flow of sand and abrasive through the separators and their associated circulation system may be easily maintained at a substantially constant rate. This avoids the possibility of sand passing through the separators to the blast machine, and also prevents static accumulations of sand at various points in the system such as would otherwise result in stratification and periodic dumping (due to vibration) of harmful surges of sand into the system.

The system may of course be controlled in any preferred manner, such as fully automatically or manually, or semi-automatically. Typically, it may be effectively controlled (after empirical determinations of the most efficient arrangements of the operative sequences, according to the conditions to be met) by means of a single programmed timer. Thus, by virtue of the arrangement of the present machine system the separator components will be operating at all times at peak efficiency, and the blast machine unit will also be operating at peak efficiency, and without requiring it to handle any appreciable amounts of debris such as would be harmful to the machines as well as detrimental to the efficiency of the overall operation.

FIG. 2 discloses a modified form of the machine system arrangement such as requires substantially less floor space but more headroom, compared to the machine system arrangement of FIG. 1. In this case, the operative components of the system are equivalents to the system arrangement of FIG. 1, and with a view to simplification of illustration and description, like components have been assigned like designating numerals. It will be noted, however, that the arrangement of FIG. 2 requires the use of only one elevator which is designated 22 in lieu of the elevators 22-34 of FIG. 1. In both cases the material from the blast cabinet 10 goes first to the separator 28 and then is directed toward separator 37 with a bypass conduit leading to temporary storage bin 44. Again, the discharge from storage bin 44 goes to the elevator feeding the separator 28. Therefore, it will be appreciated that the system of FIG. 2 may be controlled and operated so as to provide the same operative results as the system of FIG. 1; and it will be appreciated of course that although only two forms of the machine of the invention have been illustrated and described in detail hereinabove, it will be understood that various changes may be made therein without departing from the spirit of the invention or the scope of the following claims.

We claim:

1. A method for sequentially removing cores or the like and other large volume debris from workpieces such as castings and then finish-cleaning the same, which method comprises placing a workpiece on a support arranged to tumble said workpiece for shaking out a surge load of core material or other loose debris while delivering the debris to a first separator, transporting the overload material from said first separator to a second separator while diverting a portion of the overload material to a temporary bypass storage, blasting said workpiece while being tumbled with a jet of blast media to remove residual core material while conveying the debris and spent blast media in sequence to said first and second separators while closing the intake to said bypass storage, and finally surface-cleaning and finishing said workpiece by subjecting it to the operation of the same blast machine while slowly recycling back to the separators the temporarily stored debris which are previously segregated from the process system.

2. A machine for sequentially rough cleaning and knocking out hard-to-dislodge debris from workpieces and then finish-cleaning the same, said machine comprising, a workpiece receiving device adapted to turn the workpiece, a blast device arranged to throw blast media at the workpiece as it is turned, a feed device for delivering blast media to said blast device, a first separator receiving debris and spent media falling away from said

workpiece, said separator having a debris discharge and a preferred material discharge separate therefrom, said preferred material discharge normally delivering to a second separator, a bypass conveying overload material from said second separator intake to a temporary storage bin, a first valve controlling passage through said bypass, a second valve controlling discharge from said storage bin to said first separator, whereby said machine is sequentially controllable so as to initially block passage of material from said storage into said separator system while circulating material falling away from said workpiece through said separators and subsequently recycling the stored material and the reusable blast media through said separators and said blast device against said workpiece.

3. A method for sequentially rough cleaning and then finish-cleaning workpieces, which method comprises placing a workpiece on a support arranged to tumble said workpiece for shaking off a first surge load of debris material while delivering the debris to a first separator, transporting the overload material from said first separator to a second separator while at the same time diverting a portion of the overload material to a temporary bypass storage, blasting said workpiece while being tumbled with a jet of blast media to remove residual debris material while continuing to convey the debris and spent blast media in sequence to said first and second separators while closing the intake to said bypass storage as said second separator catches up to its loading, and finally surface-cleaning and finishing said workpiece by subjecting it to the operation of the same blast machine while slowly recycling back to the separators the temporarily stored debris which was previously segregated from the process system.

4. A machine for sequentially rough cleaning and then finish-cleaning workpieces, said machine comprising, a workpiece receiving device adapted to turn the workpiece, a blast device arranged to throw blast media at the workpiece as it is turned, a feed device for delivering blast media to said blast device, a first separator receiving debris and spent media falling away from said workpiece, said separator having a debris discharge and a preferred material discharge separate therefrom, a second separator arranged to receive the preferred material discharge from said first separator, a bypass for conveying material tending to overload said second separator to a temporary storage bin, a first valve controlling passage through said bypass, a second valve controlling discharge from said storage bin back to said first separator, whereby said machine is controllable so as to initially block passage of material from said storage into said separator system while circulating material falling away from said workpiece through said separators and to subsequently recycle the stored material and the reusable blast media through said separators for reuse of said blast media by said blast device against said workpiece.

5. A machine for sequentially rough cleaning and knocking out hard-to-dislodge debris from workpieces and then finish-cleaning the same, said machine comprising, a workpiece receiving device adapted to tumble the workpiece, a blast device arranged to throw blast media at the workpiece as it is tumbled, a feed device for delivering blast media to said blast device, a first elevator receiving a debris and spent blast media mixture from said blast device, a first separator receiving said mixture from said first elevator, said separator having a debris discharge and a preferred material discharge separate therefrom, a second elevator receiving said preferred material discharge, a second separator arranged to receive the discharge of said second elevator, a bypass conveying material tending to overload said second separator to a temporary storage bin, a first valve controlling passage through said bypass, a second valve controlling discharge from said storage bin to said first elevator, whereby said machine is controllable so as to initially block passage of material from said storage bin to said first separator while circulating material falling away from said workpiece through said separators

and for subsequently recycling the stored material through both of said separators and the reusable blast media therefrom to said blast device from thence against said workpiece.

6. A machine for sequentially rough cleaning and knocking out hard-to-dislodge debris from workpieces and then finish-cleaning the same, said machine comprising, a workpiece receiving device adapted to turn the workpiece, a blast device arranged to throw blast media at the workpiece as it is turned, a feed device for delivering blast media to said blast device, an elevator receiving the blast media and debris discharge mixture from said blast device, a first separator receiving said mixture from said elevator, said separator having a debris discharge and a preferred material discharge separate therefrom, said preferred material discharge normally delivering to a second separator, a bypass conveying overload material from said second

separator intake to a temporary storage bin, a first valve controlling discharge from said storage bin to said elevator, whereby said machine is controllable so as to initially block passage of material from said storage into said separator system while circulating material falling away from said workpiece through said separators and for subsequently recycling the stored material through said separators and returning the reusable blast media to said blast device.
